UNITED STATES PATENT OFFICE.

FRANZ GEDIES AND CARL SCHUNKE, OF BERLIN, GERMANY.

LAMP.

SPECIFICATION forming part of Letters Patent No. 516,925, dated March 20, 1894.

Application filed October 27, 1892. Serial No. 450,136. (No model.)

To all whom it may concern:

Be it known that we, FRANZ GEDIES and CARL SCHUNKE, of Berlin, in the Kingdom of Prussia and German Empire, have invented 5 certain new and useful Improvements in Lamps, of which the following is a full, clear, and exact description.

This invention has for its object to provide an adjustable lamp for use when working, 10 reading and the like, which may readily be brought into any desired convenient position relatively to the work, book or other object.

Reference is to be had to the accompanying drawings forming a part of this specification, 15 in which similar letters of reference indicate corresponding parts in all the figures.

Figure I is a broken side elevation of a lamp embodying our invention, partly in section. Fig. I^a is a detail vertical section of a 20 part thereof. Fig. II is a plan view. Fig. III is a front elevation of the parts shown in Fig. I^a. Fig. IV is a plan view of such parts; and Fig. V is a plan view of the base and clamp. Fig. VI is a side elevation of the same.

25 In constructing our improvement, a base is provided comprising an upright stud or post *b* and a base flange *b'*, and on said post there is sprung a tube *a*, having a lateral tubular arm *e*, the latter being formed with a longitudinal slot *f*. In the tube *e* there is fitted to slide a rod *g*, which is held in any adjusted 30 position by the wing screw *h*, and carries at its outer end a vertical plate *i*, through which the reduced outer end of said rod projects, as 35 at *k*.

The lamp *a'* of any suitable pattern is provided with a vertical arm or plate *z*, secured to the base *l* of the lamp, and formed with a vertical series of apertures *z'*, for the entrance 40 of the projecting end of the rod *g*, the lamp thus being vertically adjustable, as the rod *g* may engage the arm *z*, at any desired point in the height of the latter. The base *b*, *b'*, is clamped to any suitable support or table 45 *d*, by means of the clamp *c*, consisting of a U-shaped yoke adapted to embrace the table or the like, the top member being formed into a split ring *c'*, to permit it to pass laterally over the flange *b'*, as shown in Fig. 5, and

the bottom member of the yoke being provided with a vertically movable clamp screw *c*². By the above construction, the lamp may be clamped to any convenient bench, table, or like support, and may be readily adjusted vertically, as required. The upper engaged 50 end of the arm *z* is held against displacement by a locking sleeve *m*, which is adapted to be slid over the upper end of said arm and over the plate *i* on the rod *g*, and is formed with a hook *m'* at one side for conveniently 55 placing and removing it.

Having thus described our invention, we claim as new and desire to secure by Letters Patent—

1. The combination with a lamp, having an 60 apertured arm, a standard, a laterally disposed rod supported from the standard, said rod having a plate near its outer end through which the outer end of the rod projects for 65 engaging the apertured arm of the lamp, and a locking device consisting of a sleeve adapted to slide over said plate and the upper end of said apertured arm, substantially as described.

2. A lamp bracket comprising the vertical 70 standard *a* having a flange *b'* at its lower end, a clamp having a split or open ring to engage 75 said flange, a longitudinally slotted tubular arm projecting from the said standard, a rod 80 sliding therein and provided with a set screw extending through said slot, a vertical plate on the outer end of the rod, a projection *k* 85 extending from the outer face of the plate, a lamp carrying arm having a vertical series of apertures to engage projection *k*, and a removable sleeve *m* embracing the said plate and apertured arm, substantially as set forth.

3. The combination with the vertical standard having a lamp carrying arm and provided at its lower end with a base flange *b'* of the clamp comprising a yoke adapted to embrace the table or other article and provided on the end of its upper member with a ring *c'*, having a split or opening to pass the standard to permit the said ring to rest on the upper side of the flange *b'* and the vertical screw *c*² extending through the lower member substantially as set forth.

4. In a lamp bracket a rod provided at its end with a vertical plate and a projection beyond the outer face of said plate a lamp carrying arm having an aperture to engage said 5 projection and a sleeve removably embracing the said plate and apertured arm all substantially as and for the purposes set forth.

In witness whereof we have hereunto set our hands in presence of two witnesses.

FRANZ GEDIES.
CARL SCHUNKE.
